UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

FUSE.

1,404,858.

Specification of Letters Patent. Patented Jan. 31, 1922.

Application filed May 2, 1918. Serial No. 232,141.

To all whom it may concern:

Be it known that I, PAUL M. HENGSTENBERG, a subject of the German Emperor, and a resident of Wilkinsburg, in the county of Allegheny and State of Pennsylvania, have invented a new and useful Improvement in Fuses, of which the following is a specification.

My invention relates to fuses and particularly to multiple refillable fuses.

One object of my invention is to provide a device of the above-indicated character that shall be simple and durable in construction and be composed of relatively few parts.

Another object of my invention is to provide a multiple refillable fuse device in which all of the component parts are so inter-related as to form a neat and compact device that may be reset, placed in, and removed from, its operating position, disassembled and refilled in a very simple and expeditious manner without the use of tools of any kind.

Heretofore, certain multiple refillable fuses have severally comprised a plurality of cartridges adapted to individually enclose a single fusible element and have been mounted on cumbersome and expensive supporting devices embodying relatively large numbers of parts. These devices have usually been impractical by reason of their relatively great size, as compared with the volume of current traversing the same.

In other multiple refillable fuse devices employing a single container for a plurality of fusible elements, the use of springs, screws, rivets and complicated structures has rendered them impractical from both structural and operative standpoints.

In practicing my invention, I provide a multiple refillable fuse device that overcomes all of the above-mentioned objections in that it embodies substantially a minimum number of parts of such relation as to permit its operation, assembly, disassembly, mounting and demounting and that may be readily refilled without resort to tools of any kind.

Figure 1 of the accompanying drawings is a side view of a fuse device embodying my invention; Fig. 2 is a view, partially in section and partially in elevation, of the device

as shown in Fig. 1, and Fig. 3 is an end view, partially in section and partially in elevation, 55 of the same.

Screws 1, washers 2 and nuts 3 rigidly secure terminal clips 4 to an insulating supporting member 5, or any other suitable structure, such as a switchboard panel. The 60 clips 4 embody curved arms 6 having inwardly projecting side portions 7 and intermediate contact arms 8, for a purpose to be hereinafter described.

A cartridge 9 comprises a hollow cylindrical casing 10 of fiber or other suitable insulating material that is adapted to be rotatably supported by the clips 4 and has exteriorly knurled portions 11 to permit of ready turning by hand, when in operative 70 position between the arms 6, as shown in the drawings.

A cylindrical insulating core member 12, having its external diameter slightly less than the internal diameter of the casing 10, 75 is disposed therein and is provided with a plurality of semi-cylindrical longitudinal grooves or recesses 13 having enlarged portions 13^a of similar shape at their ends. Fusible elements 14 loosely extend through 80 the grooves 13 and are provided, at their ends, with terminal members 15 having enlarged discoidal heads 16 disposed in the enlarged end portions 13^a of the grooves 13 and hollow cylindrical shank portions 17 85 that extend inwardly into the smaller-diameter portions of the grooves. The walls of the enlarged portions 13^a of the grooves 13 embrace the heads 16 over slightly more than one-half their circumferences, which relation, in conjunction with a certain amount of compressibility of the material of the core member 12, permits the members 15 to be 90 snapped into and out of position or held securely therein to maintain the elements 14 in the grooves 13. The elements 14 extend through the hollow shank portions of the members 15 to the concave faces of the heads 16 to which they are securely soldered.

Inwardly extending portions 18 at the 100 ends of the casing 10 extend between and so embrace portions of the periphery of the heads 16 as to prevent relative rotative movement between the casing and the core member 12 but do not prevent the ready removal of the latter longitudinally. 105

The contact arms 8 are provided with rounded knobs or buttons 19 at the outer bent ends 20 thereof to engage the concave faces of the terminal member heads 16 of the 5 elements 14. The arms 8 are biased inwardly so that, when the cartridge 9 is rotatively moved to substitute a complete element 14 for one that has been ruptured, the knobs 19 ride easily out of the recesses in the 10 heads 16, over the intervening spaces and into engagement with the concave faces of the next adjacent terminal heads 16.

Apertures 21, corresponding, in circumferential position, to the recesses or grooves 13, may be filled with any suitable substance, such as wax or paraffine, for the purpose of indicating which, if any, of the elements 14 have been ruptured.

The portions 7 prevent longitudinal 20 placement of the cartridge 9 when the latter is in position in the clips 4.

After the rupture of all of the elements 14, the cartridge 9 may be pulled from the arms 6 of the clips 4, an end thrust exerted 25 upon the core member 12 to remove the same from the casing 10 and the members 15 lifted from their positions in the grooves 13. New elements 14, including terminal members 15, may then be snapped into position, the core 30 member pushed into the casing 10 and the latter snapped back into position within the arms 6.

The absence of screws, bolts, rivets, springs, and other parts in the cartridge 35 proper that comprises only two parts 10 and 12, the fact that each of the clips 4 and its associated portions 7 and arms 8 are of one piece of material, the ease of operation and the ready renewal of the ruptured elements 40 are features which combine to form an extremely simple, economical and readily operable device.

While I have shown and described a particular form of my invention, many changes 45 may be made therein without departing from the spirit and scope thereof, as set forth in the appended claims.

I claim as my invention:

1. A multiple-refillable fuse device comprising a single containing member, a plurality of readily renewable fusible elements 50 therein, and a supporting means for directly connecting said elements in a circuit by a rotative movement of said containing member and supporting the latter so that it 55 may be readily removed from said means by a transverse movement with respect to the axis of the same.

2. A multiple-refillable fuse device comprising a tubular casing, relatively-rotative 60 supporting means embracing the casing, a core member disposed in the casing and having a plurality of longitudinal grooves, a plurality of fusible elements disposed in said 65 grooves and cooperating with the casing to

prevent relative rotative movement between the casing and the core member and means for connecting said elements to a circuit.

3. A multiple-refillable fuse device comprising a hollow cylindrical insulating casing open at each end, an insulating core member therein having a plurality of longitudinal grooves, a plurality of fusible elements disposed in said grooves and means engaging the outer surface of said casing 75 for rotatively supporting the same and selectively engaging the ends of said elements to connect the same in a circuit.

4. A multiple-refillable fuse device comprising a single tubular containing member, 80 a core member having a plurality of longitudinal recesses therein loosely disposed in the casing and a plurality of fusible elements disposed in said recesses and cooperating with the containing member to prevent relative rotative movement between 85 the latter and the core member.

5. A fuse device comprising a cylindrical core member having a plurality of longitudinal grooves, a plurality of readily removable fuse elements disposed in said grooves, terminal members for said elements, an enclosing casing for said core member and said fuse elements, stationary terminal members for supporting said casing, 95 and for engaging the terminal members of one of said elements, the said stationary terminal members being adapted to be placed in a similar relation to any of the elements by rotative movement of said casing. 100

6. A fuse device comprising a tubular casing, a core member conforming thereto and having an outer longitudinal recess, said recess being enlarged at the ends of said core member, a fusible element disposed in said 105 recess, and terminal members attached to the ends of said element and shaped to conform to portions of said recess.

7. In a fuse device, the combination with a plurality of fusible elements, of a cartridge comprising two parts only for supporting and protecting the same, and means for selectively connecting said elements to a circuit. 110

8. A multiple-refillable fuse device comprising a two-part cartridge, a plurality of fuse elements disposed therein and having exposed heads at the transverse faces thereof, supporting means for said cartridge and means whereby a rotative movement of the 115 cartridge with respect to the supporting means positions one of said elements in a circuit. 120

9. A multiple refillable fuse comprising a cylindrical core member having longitudinal grooves in its outer surface, said grooves having enlarged portions at the ends thereof, a plurality of fusible elements each having a portion disposed in an enlarged portion 125 of one of said grooves, and a cylindri- 130

cal casing for the core cooperating with the enlarged portions of the fusible elements to prevent relative rotative movement between the core and the casing.

- 5 10. A multiple refillable fuse comprising a cylindrical core member having longitudinal grooves in its outer surface, said grooves having enlarged portions of slightly greater than half a circle in contour at the ends of
  - 10 10 the core, a plurality of fusible elements each having a cylindrical portion disposed in an enlarged portion of one of said grooves, and a cylindrical casing for the core cooperating with the enlarged portions of the fusible
  - 15 15 element to prevent relative rotative movement between the core and the casing.
11. A fuse device comprising a supporting member of yieldable material having a longitudinal groove therein, said groove
- 20 20 having an enlarged portion of slightly greater than half a circle in contour and a

fusible element in said groove having a cylindrical portion substantially filling the enlarged portion of the groove, the arrangement permitting the fusible element to be 25 firmly supported and to be snapped into and out of position in the groove.

12. A fuse device comprising a supporting member having a longitudinal groove therein, said groove having an enlarged portion 30 of slightly greater than half a circle in contour and a fuse member in said groove having a cylindrical portion substantially filling the enlarged portion of the groove, one of said members being constructed of yieldable material to permit the fuse member to be firmly supported and to be snapped into and out of position in the groove.

In testimony whereof, I have hereunto subscribed my name this 29th day of April, 40 1918.

PAUL M. HENGSTENBERG.
